GAS RANGE

Glenn O. Galloway, McLean, Va., assignor to
Servel, Inc., New York, N. Y., a corporation of
Delaware

Application January 28, 1948, Serial No. 4,839

6 Claims. (Cl. 126—39)

1

This invention relates to gas ranges and particularly to means for distributing, filtering and preheating air that flows into the combustion chamber in which the oven burner is located.

This application relates back for common subject matter to my earlier application Serial Number 602,063, filed June 28, 1945, now abandoned. This application is a continuation in part of the foregoing abandoned application.

In gas stoves generally and domestic gas ranges particularly, it is desirable that the intake air for the oven burner be adequate and that this air be uniformly distributed in the combustion chamber in which the oven burner and pilot are located. It is also desirable that the intake air be free of lint, dust and other foreign matter and that this air be supplied to the different burners in such manner as not to produce or set up drafts upon the burners. It is further desirable that the intake air be preheated, thus increasing the over-all efficiency of the oven. Furthermore, it is desirable and necessary with domestic gas ranges that the floor beneath the gas range be insulated from the relatively high temperature of the oven burner.

By this invention, I have accomplished the above and other objects and advantages in a simple, practical and efficient manner, by providing a permeable pad of thermal insulating material below the combustion chamber in which the oven burner is located, and by providing a baffle plate above this insulating material. The insulating pad may be self supporting and form the bottom of the combustion chamber, or a bottom member, uniformly perforated throughout its entire area, may be provided as a support for the insulating pad.

The insulating pad is so arranged relative to the combustion chamber that substantially all intake air, primary, secondary and excess, that flows into the combustion chamber must first pass through this insulating pad. The baffle plate is arranged above and spaced from the insulating pad in such a manner as to prevent radiation or convection of heat from the flames of the gas burner directly to the insulating pad, while at the same time permitting substantially free flow of ambient air into and through all parts of the insulating pad. In this manner, the pad is uniformly cooled by the flow of ambient air therethrough, and the air is preheated in passing through the pad and beneath the baffle plate. The pad is treated with a substance which renders the insulating material a filter whereby entrained foreign matter is filtered out of the air

2

in passing through the pad. The pad covers the entire bottom of the combustion chamber, thereby insulating the floor beneath the range. While I have shown but one pervious wall, all outside walls of the combustion chamber may be made pervious, whereby these walls will be cooled by air flowing into the combustion chamber.

Referring now to the accompanying drawing, wherein a preferred embodiment of this invention is illustrated, and in which:

Fig. 1 is a broken perspective view, partly in section, of a gas range illustrating my invention;

Fig. 2 is a transverse vertical sectional view taken substantially on line 2—2 of Fig. 1; and

Fig. 3 is an exploded perspective view of a housing, an insulating pad and a baffle plate.

The gas range 10, illustrated in the drawings, includes an oven 11 provided with a burner compartment or combustion chamber 12, a broiler or auxiliary oven 13, a utility drawer 14, top burners 15 and a supporting base 16. The oven 11 and combustion chamber 12 are each provided with doors, not shown.

In accordance with this invention, the combustion chamber 12 is provided with a perforated box-like housing or bottom member 17 adapted to receive and hold a pad of insulating and filtering material 18. As shown in Fig. 3, member 17 is perforated to such an extent that air is free to flow through substantially the entire bottom area thereof. While I do not wish to be limited to particular materials, it has been found in practice that a pad of permeable material, such as glass wool or the like, coated with a suitable noninflammable sticky substance such as, for example, a heavy viscous oil, provides an excellent insulating and filtering pad. A baffle plate 19 is removably supported in spaced relation above the pad 18, as by four integral legs 20 which rest upon opposite top edges of member 17. The baffle plate is provided with perforations 21 along each of its transverse edges. As shown, baffle plate 19 is smaller than the pad 18 so as to permit unobstructed flow of air from beneath the baffle plate into the combustion chamber. Furthermore, the baffle plate is so located and spaced relative to the insulating pad, that air flowing into the combustion chamber, flows upward through the interstices of the entire mass of the insulating pad, whereby the velocity of such air is materially reduced and the air enters the combustion chamber quietly without causing any draft on the burner. A gas burner 22 provided with a suitable pilot, not shown, is supported by 45 50 55 the baffle plate. The burner 22 is provided with

a primary air mixing tube 22^a located within the combustion chamber.

The oven 11 is formed with a bottom 23 provided with a slot 23^a along each transverse edge and with perforations 24 along the front edge thereof. The top 25 of the oven lining is provided with a row of perforations 26 along each transverse edge thereof, which perforations open into a horizontal flue 27. The horizontal flue 27 opens into a vertical flue 28 provided with louvers 29 on the top portion thereof. A dilution flue 30 leads from the lower rear portion of the range and opens into the vertical flue. As shown in Fig. 2, base member 16 is provided with an elongate opening 31 which extends along the rear of the range beneath the combustion chamber 12. The oven is provided with a drip pan, not shown, but which is spaced from and traverses substantially the entire bottom of the oven so as to protect the pad 18. The oven is also provided with suitable racks and rack guides, not shown.

In operation, assuming that the oven burner is lighted, a chimney effect is produced in the vertical flue 28 which causes air to be drawn into the combustion chamber 12. All intake air, that is primary, secondary and excess air, that enters the combustion chamber, passes through the elongate opening 31 at the rear of the base member 16 and into and across the space beneath the combustion chamber. As illustrated by the arrows in Fig. 2, the air then flows upwardly through the perforations in bottom member 17, through the interstices in the insulating pad 18 into the space between the insulating pad and the baffle 19. The air then flows from beneath the baffle member through the apertures 21 and through the spaces provided between the peripheral edges of the baffle and the side walls of the combustion chamber, into the combustion chamber proper. Air also flows directly upward through the margins of the insulating pad and joins the air flowing from beneath the baffle into the combustion chamber. The blanket of ambient air flowing into and across the space beneath the bottom member 17 picks up heat and would otherwise be radiated to the floor beneath the range. In passing through the apertures of the bottom member and through the insulating pad the intake air tends to uniformly cool the entire bottom of the combustion chamber. Furthermore, the air in passing from beneath the baffle 19 tends to pick up additional heat which would otherwise be radiated to the insulating pad. In passing through the insulating pad the air deposits entrained solid matter upon the sticky substance with which the pad is treated, thus protecting the oven burner and pilot from the effects of lint, dust or other foreign particles. The spacing of the insulating pad 18 and the baffle plate 19 is such that sufficient resistance is offered to the flow of air passing into the combustion chamber so that this air reaches the burner without setting up any draft. The products of combustion and heated air flow from the combustion chamber 12 through the slots 23^a and the perforations 24 into the oven 11. From the oven, the products of combustion and heated air pass through the perforations 26 in the top

lining of the oven, through horizontal flue 27, through vertical flue 28 and out through the louvers 29.

Although a single embodiment of this invention has been shown and described for purposes of illustration, the invention may obviously take other forms and be variously applied within the scope of the following claims.

What is claimed is:

1. In a gas range, a combustion chamber, said combustion chamber having at least one permeable external wall, a gas burner in said combustion chamber, so located as to heat said permeable wall and means for permeating ambient air into said combustion chamber through interstices of substantially the entire mass of said permeable wall, whereby the air is heated in passing through the interstices of said wall and the temperature of the external surface of said wall is maintained at approximately room temperature during the operation of said gas burner, said last named means including a flue for conveying products of combustion from said combustion chamber.
2. In a gas range as set forth in claim 1 wherein said permeable wall includes a pad of porous thermal insulating material through the pores of which the ambient air permeates.
3. In a gas range as set forth in claim 2 wherein the pad of insulating material is arranged in a manner that substantially all primary, secondary and excess air that reaches the combustion chamber passes through the pores of said insulating material.
4. In a gas range as set forth in claim 3 wherein a baffle plate is located in the combustion chamber between the pad of insulating material and the gas burner.
5. In a gas range as set forth in claim 4 wherein the baffle plate is spaced from the pad of insulating material, whereby ambient air permeates through the pad of insulating material and across a surface of said baffle plate.
6. In a gas range as set forth in claim 5 wherein the pad of insulating material is treated with a substance which renders said pad an air filter as well as a thermal insulator, whereby all air that passes through the insulating material is filtered before reaching the combustion chamber.
